2,087,588

ANTISEPTIC AND GERMICIDAL COMPOSITION

William E. Austin, New York, N. Y.

No Drawing. Application July 30, 1934,
Serial No. 737,599

10 Claims. (Cl. 167—31)

This invention relates to new antiseptic and germicidal compositions, and method for producing them, the said compositions comprising combinations of casein with phenolic substances, especially alkylated phenols and derivatives, more particularly those conforming to the general formula

where R is phenyl or halogenophenyl; X is any alkyl radical; Y is H or any alkyl radical; and m is 1 or 2.

15 I have found that under certain conditions to be described more fully, casein forms combinations with phenolic substances, yielding compositions which possess the desirable antiseptic and germicidal qualities of the original phenolic derivatives, and in addition many valuable and desired qualities and characteristics, which constitute a distinct and signal improvement in antisepsis, and antiseptic therapy.

Included in the scope of this invention are the 25 antiseptic compositions comprising the combinations of casein with primary, secondary or tertiary mono-alkyl phenols; casein with primary, secondary or tertiary mono-alkyl chloro-phenols; casein with primary, secondary or tertiary mono-30 alkyl resorcinols; casein with primary, secondary or tertiary mono-alkyl chloro-resorcinols; casein with symmetrical dialkyl resorcinols; casein with 35 asymmetrical dialkyl resorcinols; casein with primary, secondary or tertiary mono-alkyl catechols; casein with primary, secondary or tertiary mono-alkyl chloro-catechols; casein with primary, secondary or tertiary mono-alkyl hydroquinones; casein with primary, secondary or 40 tertiary mono-alkyl chloro-hydroquinones.

45 Asymmetrical dialkyl resorcinols have been described in my pending application Serial No. 633,086, filed Sept. 14, 1932.

Secondary alkyl resorcinols have been described in my pending application Serial No. 682,270 filed July 26, 1933.

Primary alkyl chloro-resorcinols have been described in my pending application Serial No. 682,271 filed July 26, 1933.

50 Secondary alkyl chloro-resorcinols have been described in my pending application Serial No. 682,272 filed July 26, 1933.

Tertiary alkyl chloro-resorcinols, tertiary alkyl chloro-catechols, and tertiary alkyl chloro-hydro-

droquinones have all been described in my pending application Serial No. 715,495 filed Mar. 14, 1934.

The other phenolic compounds have been described elsewhere, and are readily available.

5 The new compositions of the present invention may be prepared in a simple, efficient and inexpensive manner, by mixing a hot, neutral, aqueous suspension of the desired phenolic substance with granulated or powdered casein, stirring, and after allowing to cool until the mass has coagulated, filtering off, and drying. The proportion of casein to phenolic compound may vary over a wide range, although I prefer to use an amount of the phenolic substance corresponding to from 5% to 100% of the weight of the casein.

10 The new compositions are all granular or powdery amorphous substances, varying in color from pale cream to yellow-brown. While the 20 exact nature of the casein-phenol compounds has not been determined, the combination seems to be more intimate than a simple mixture. Extraction of any of the compounds at ordinary room temperatures, with alcohol (ethyl) removes only 25 a part of the phenolic constituent, although alcohol is one of the best solvents for the phenolic substances. This alcoholic extract may be used as a means of identifying the particular casein-phenol composition, by determining the boiling 30 point, or melting point of the extracted phenol, or by other customary tests.

15 The casein-phenol compositions are all homogeneous, stable products, which are admirably adapted for use in internal as well as external 35 antiseptic and germicidal therapeutic administration. The compositions may be used as dusting powders, wet-packs or compresses for external antisepsis; or in powder form, and if desired, compressed into tablets, pellets or pills for internal use.

20 In medical practise, phenolic substances of the type above indicated have been employed hitherto in the form of dilute solutions in alcohol, glycerine, glycols or oils, mainly for external treatment. 45 In higher concentrations, solutions in oil encased in capsules have been used in internal therapy. The compositions of casein with phenols of the present invention afford many advantages over the previously employed solutions of antiseptic phenols, especially for internal treatment. The casein compounds are much simpler and cheaper to prepare. They can be administered with greater ease, convenience, and less objection or 50 55

resistance of the patient, because they are in solid form, as powders, pills or tablets. Much higher concentrations of the desired phenolic substance can be used in the casein compositions, without any escharotic or irritant action on the mucous tissues of the oral and alimentary tracts. The use of relatively high concentrations of the phenolic constituent is desirable in the treatment of certain intestinal ailments such as abscesses, ulcers, putrefactive conditions, parasitic organisms of animal or vegetable nature, and in general antisepsis of the urinary and alimentary tracts. The dosage naturally depends on the particular condition to be treated and therefore must be left to the physician's discretion.

Because of the fact that the antiseptic and germicidal compositions of the present invention are apparently rather intimate combinations of casein with the respective phenolic substances, possibly even true chemical compounds, the desired antiseptic and other beneficial properties of the phenols are made available in a gradual, uniform and effective fashion in contact with the body fluids; and in the intestinal tract, the digestion of the casein constituent of the composition effects the liberation of the phenol, permitting it to exert its beneficial activity at the desired locus.

Inasmuch as the various phenolic substances differ in the intensity, character and specificity of their respective qualities, it may be found desirable to combine two or more phenols with casein in the same composition, in order to obtain simultaneously the beneficial effects of the phenols concerned. This may be done either by mixing the separate casein compositions of the respective phenols, or by preparing a casein composition containing the phenols together.

The following examples illustrate the method of preparing the compositions of the present invention:

1. 10 grams of ethyl-hexyl resorcinol are mixed with 500 cc. of hot water (75° C.). While stirring constantly, 25 grams of granular, edible casein are added quickly. Reaction takes place with disappearance of the phenol from the aqueous portion of the mixture, and simultaneous darkening of the casein. Stirring is continued, and the temperature maintained at 75°, until the product coalesces into a heavy lump. Allow to cool to room temperature, and filter. (The filtrate when tested shows complete absence of phenolic substance.) The filter cake is air dried, yielding a brownish granular mass, which can be easily powdered.

2. 25 grams p-ter.-amyl phenol are added to 500 cc. water, and heated to about 85° C. To this mixture is added while stirring, 25 grams granular casein, and the stirring is continued until the mass coagulates. It is then filtered off, and air dried, yielding a pale cream colored mass, easily powdered.

3. 5 grams of sec. octyl chloro-resorcinol (derived from methyl hexyl carbinol) and 5 grams hexyl resorcinol are mixed with 500 cc. water at 75° C., and while stirring vigorously 50 grams of casein are added, and stirring continued and temperature kept at 75° C. until the mass coagulates. After cooling to room temperature, the mass is filtered off, and air dried. A slightly yellowish granular mass is obtained, which crumbles easily.

The following compositions have been made

by the method described in the above examples:

	Parts
Casein 100 parts p-ter. amyl phenol M. P. 92-93° C.	25
Casein 100 parts p-ter. amyl phenol	100
Casein 100 parts p-sec. hexyl phenol B. P. 265-275° C.	40
Casein 100 parts p-di-isobutyl phenol M. P. 83° C.	100
Casein 100 parts o-phenyl phenol M. P. 56° C.	25
Casein 100 parts p-amin m-cresol B. P. 137-139° C./15 mm.	40
Casein 100 parts p-ter. amyl o-chlorophenol B. P. 105-10° C./2 mm.	25
Casein 100 parts n-hexyl resorcinol M. P. 67-69° C.	25
Casein 100 parts n-hexyl resorcinol	100
Casein 100 parts n-heptyl resorcinol M. P. 73-75° C.	40
Casein 100 parts n-hexyl chlororesorcinol B. 165-175° C./4 mm.	40
Casein 100 parts n-heptylchlororesorcinol B. 201-03° C./15 mm.	25
Casein 100 parts n-heptylchlororesorcinol	100
Casein 100 parts n-octyl chlororesorcinol B. 185-95° C./5 mm.	100
Casein 100 parts sec. hexyl resorcinol B. 170-78° C./7 mm.	40
Casein 100 parts sec. heptylresorcinol B. 155-65° C./3 mm.	25
Casein 100 parts sec. octylresorcinol B. 190-210° C./1 mm.	100
Casein 100 parts sec. hexylchlororesorcinol B. 170-90° C./4 mm.	10
Casein 100 parts sec. heptyl chlororesorcinol B. 140-50° C./4 mm.	40
Casein 100 parts sec. octylchlororesorcinol B. 160-75° C./5 mm.	5
Casein 100 parts sec. octylchlororesorcinol	100
Casein 100 parts di-isobutyl resorcinol M. 101-2° C.	40
Casein 100 parts ter. amyl chlororesorcinol B. 145-50° C./7 mm.	25
Casein 100 parts ter. butylchlororesorcinol B. 135-40° C./5 mm.	40
Casein 100 parts di-isobutylchlororesorcinol M. 103-4° C.	5
Casein 100 parts di-isobutylchlororesorcinol	100
Casein 100 parts ter. amyl chlorohydroquinone M. 123-5° C.	40
Casein 100 parts ter. amyl chlorocatechol B. 135-40° C./3 mm.	25
Casein 100 parts di-isobutylchlorocatechol B. 150-65° C./5 mm.	100
Casein 100 parts di-hexyl resorcinol B. 210-20° C./6-8 mm.	55
Casein 100 parts di-butyl resorcinol B. 180-95° C./8 mm.	100
Casein 100 parts ethyl-hexyl resorcinol B. 172-82° C./2-3 mm.	60
Casein 100 parts ethyl-hexyl resorcinol	25
Casein 100 parts ethyl-hexyl resorcinol	100
Casein 100 parts methyl-hexyl resorcinol B. 170-80° C./5 mm.	40
Casein 100 parts methyl-heptyl resorcinol B. 172-80° C./4-5 mm.	65
Casein 100 parts methyl-heptyl resorcinol	100
Casein 100 parts methyl-heptyl resorcinol	25
Casein 100 parts sec. octyl p-chlorophenol B. 155-60° C./3 mm.	70

I claim:

1. Antiseptic and germicidal compositions prepared by treating in neutral, aqueous medium

at approximately 75° C., casein with a phenol of the general formula

where R is phenyl or halogenophenyl; X is any alkyl radical; Y is H or any alkyl radical; and m is 1 or 2.

10 2. Antiseptic and germicidal compositions prepared by treating in neutral, aqueous medium at approximately 75° C., casein with 5% to 100% of its weight of a phenol of the general formula

20 where R is phenyl or halogenophenyl; X is any alkyl radical; Y is H or any alkyl radical; and m is 1 or 2; and separating the coagulated compound after cooling, and drying at ordinary temperatures.

25 3. The method of preparing antiseptic and germicidal compositions, which consists in treating in neutral aqueous medium at approximately 75° C., casein with 5% to 100% of its weight of a phenol of the general formula

35 where R is phenyl or halogenophenyl; X is any alkyl radical; Y is H or any alkyl radical; and m is 1 or 2; separating the coagulated compound after cooling, and drying at ordinary temperatures.

40 4. Antiseptic and germicidal compositions prepared by treating in neutral aqueous medium at approximately 75° C., casein with 5% to 100% of its weight of sec. octyl chloro-resorcinol, sep-

arating the coagulated compound after cooling, and drying at ordinary temperatures.

5 5. The method of preparing antiseptic and germicidal compositions which consists in treating in neutral aqueous medium, at approximately 75° C. casein with a phenolic substance of the general formula

15 where R is phenyl or halogenophenyl; X is any alkyl radical; Y is H or any alkyl radical; and m is 1 or 2; and separating the coagulated compound.

6. Antiseptic and germicidal compositions prepared by treating casein with sec. octyl chloro-resorcinol in neutral aqueous medium at approximately 75° C.

7. Antiseptic and germicidal compositions prepared by treating casein with ethyl-hexyl resorcinol in neutral aqueous medium at approximately 75° C.

8. Antiseptic and germicidal compositions prepared by treating casein with p-ter. amyl phenol in neutral aqueous medium at approximately 75° C.

9. Antiseptic and germicidal compositions prepared by treating casein with 5% to 100% of weight of ethyl-hexyl resorcinol in neutral aqueous medium at approximately 75° C., separating the coagulated compound after cooling and drying at ordinary temperatures.

30 10. Antiseptic and germicidal compositions prepared by treating casein with 5% to 100% of its weight of p-ter. amyl phenol in neutral aqueous medium at approximately 75° C., separating the coagulated compound after cooling and drying at ordinary temperatures.
